UNITED STATES PATENT OFFICE

CLARENCE M. WILKINSON, OF AKRON, OHIO

WASTE DISPOSAL CHUTE

Application filed October 16, 1926. Serial No. 141,935.

This invention relates to waste disposal or like chutes.

One purpose or object of the invention is to provide an improved chute effectively safe-guarded against the fire hazard.

Another purpose of the invention is to provide an improved intake for chutes.

Another purpose of the invention is to provide automatically operable means for creating a draft in the chute should a fire occur therein to carry off the heat and gases of combustion.

Particularly the invention has for an object the provision, in combination with a chute of this type, of means for preventing a rush of heat or flame out of the intakes due to a fire in the chute, including double door intakes and means for creating a draft in the chute when a fire occurs therein, whereby the heat and products of combustion are dissipated.

The foregoing and other objects are obtained by the chute disclosed in the accompanying drawings and described below with more particulars. It is to be understood that the invention is not limited to the specific form thereof shown and described.

Of the accompanying drawings,

Figure 1 is a section through a building having the improved chute mounted therein, the chute being shown in elevation;

Figure 2 is a section on line 2-2 of Figure 1;

Figure 3 is a section on line 3-3 of Figure 1;

Figure 4 is a section on line 4-4 of Figure 1;

Figure 4^a is a detail side elevation of the top of the chute with one chute closure broken away;

Figure 5 is a front elevational detail of the intake;

Figure 6 is a detail side elevation thereof;

Figure 7 is a section on line 7-7 of Figure 5;

Figure 8 is a section on line 8-8 of Figure 6;

Figure 9 is an enlarged detail side elevation of the intake operating device showing the parts in their neutral positions;

Figure 10 is a similar view, partly broken away, showing the positions of the parts when the outer hopper closure is opened;

Figure 11 is a similar view showing the positions of the parts when the outer hopper closure is shut and the inner door opened; and

Figure 12 is a similar view showing the positions of the parts at the completion of the intake operation, the inner door having shut by gravity.

Referring to the drawings, the chute is shown as made up of a plurality of floor sections 10, 10, preferably supported at each floor by flange rings 11, 11 and each having an intake section thereon at 12. The top floor section 10 preferably projects through the roof of the building at 13 and a small section 14, carrying closures 15, 15 pivoted at 16, 16 thereon and provided with counterweights 17, 17, is mounted on the top floor section. The section 14 is cut away as at 14^a, 14^a to provide vents for carrying off odors and fumes. A discharge section 18 is secured on the lower floor section 10 so as to project down into the basement of the building, this section being supported on one or more piers or posts 19. The section 18 has a lateral discharge portion 20 having a closure 21 balanced by a counterweight 22 on an arm 23. The floor sections preferably are enclosed in a wall 24 providing a shaft extending vertically through a convenient part of a building, such that the intakes for the chute, shown generally at 25, 25, face upon a corridor or the like.

Fire hazard is minimized by provision of intakes 25 of double closure construction so controlled that one or the other of the closure members will always be shut, the construction and operation of the intakes being more fully described below, and also by the provision of a suitable sprinkler adjacent the bottom of the chute, as indicated at 26, this sprinkler being preferably of the automatic type. The fire hazard is further minimized by the provision of automatically releasable means including a chain 27 having connections to each closure 15 for holding closure 15 shut and secured to the inner wall of the

chute by a link 28 fusible by the heat of a fire in the chute to permit closures 15 to open. A suitable hand hole and closure therefor may be provided at 29 to permit replacement of fusible links.

5 The intakes 25 and operating mechanism therefor are shown in detail in Figures 5 to 12. Each section 12 has a lateral extension 25^a which slopes downwardly into the chute 10 and has an inner closure 30 pivoted thereon at 31 and an outer hopper-shaped closure 32 pivoted thereon at 33 which, when shut, is flush with the wall 24. The inner closure 30 is adapted to close by gravity and has an operating arm 34 connected thereto. The outer closure 32 has an operating arm 35 connected thereto to which is connected a spring 35^a normally urging the closure 32 shut.

15 The operating mechanism for closures 32 and 30 includes a cam link member 36 connected to a pedal lever 37 at 38, the lever 37 being pivoted on a vertical channel member 39 and being operable upwardly as well as downwardly by provision of a second pedal 20 lever 41 pivoted at 42 and having a slotted end 43 engaging a pin 44 on lever 37. Pedal levers 37 and 41 project outwardly beneath the intakes, preferably in a recess 45, so that they will not obstruct the corridor on which 25 the intakes open.

30 The cam link member 36 is designed to open and close the outer and inner closures in the desired sequence and also to lock the inner closure shut when the outer closure is being 35 opened. To this end the link member 36 is formed with a cam slot 46 in which is operable a pin 47 secured on arm 34 and is also formed with a slot 48 in which projects a pin 49 on arm 35. Into slot 48 there projects 40 a guide flange 50 formed on a member 50^a secured on link 36.

45 The above parts are shown in neutral position in Figure 9. The bottom edge of slot 48 is adapted, upon upward movement of link 36, to engage pin 49 to swing the arm 35 upwardly and thus open outer closure 32, the portion 46^a of cam slot 46 being designed to permit the cam link 36 to move relative to pin 47 so that link 36 may swing to the left 50 (Figure 10) so as to effect this movement of arm 35, the portion 46^a of the cam slot 46 also serving to lock closure 30 shut by engagement with pin 47. An auxiliary latch 51 may be pivoted at 52 so as to swing by gravity 55 under arm 34 but adapted to be held away from said arm by engagement of arm 35 with the lower end 51^a thereof excepting when arm 35 is swung upwardly to open the outer closure.

60 Referring again to Figure 9, the portion 46^a of slot 46 is designed to permit downward movement of link 36 permitting it to swing so that closure 32 will be swung shut by engagement of the side edge of slot 48 with pin 65 49 to close the outer closure and thus bring

the parts back to the positions shown in Figure 9.

As best illustrated in Figure 11, the portion 46^b of slot 46 is designed for engagement with pin 47 to swing arm 34 downwardly upon continued movement of link 36 downwardly, link 36 being guided in its downward movement by engagement of flange 50 with pin 49 which prevents link 36 from swinging to the left (Figure 11).

70 As best shown in Figure 12, the portion 46^c of cam slot 46 is designed to permit closure 30 to swing shut by action of gravity when pin 47 rides over to the right end of cam slot portion 46^b, this action being such as to swing link 36 slightly to the left so that pin 49 passes over top and in back of flange 50 and permits movement of link 36 upwardly to its neutral position shown in Figure 9 without any effect 75 on either of the closures.

80 In the operation of the intake, the right pedal 41 is depressed to move cam link 36 upwardly, opening the outer closure 32 and locking the inner closure 30 shut; the refuse is deposited in hopper 32; the left pedal 37 is then depressed, first closing closure 32, which action is assisted by spring 35^a or other suitable means which holds this closure shut; then opening closure 30, which permits the waste to fall into the chute; and finally permitting the latter to close by gravity.

85 It will appear from the foregoing that the double intake prevents odors, gases or flame from passing out of the intake when refuse is deposited in the chute. Moreover, if combustion should take place in the chute, fusing of link 28 results in creating a draft in the chute, tending to draw air inwardly at the intakes, the latter, because of the double construction, preventing leakage of any considerable air into the chute in this manner, and thus providing for the creation of a strong draft at the bottom of the chute, whereby the heat and fumes will be effectively dissipated. In addition, the automatic sprinkler 26 will be operated to quench the burning refuse.

90 Modifications of the invention may be resorted to without departing from the spirit thereof or the scope of the appended claims.

115 What is claimed is:

1. A waste disposal chute including double closure intakes, and means for operating the closure including an arm connected to each closure and a single element for actuating the arms so that one of the closures is shut while the other is open, said element having cam slots therein and a pin on each arm projecting into each cam slot, each cam slot having a portion for opening each closure and one cam slot having a portion for permitting the member to move to open the other closure.

120 2. A waste disposal chute including double closure intakes, both of said closures being

- normally shut, and means for operating the closures including an arm connected to each closure and a single element for actuating the arms so that one of the closures is shut while the other is open. 5 hinged hopper, an inner pivoted closure, said hopper and said closure being normally shut, a single member for operating the closures so that one or the other will always be shut, and a pedal lever system for operating the member. 70
5. A waste disposal chute having double closure intakes, including, in combination, an outer pivoted closure and an inner pivoted closure, each of said closures being yielding- ly urged to shut positions, and common means for operating the closures so that one or the other is always shut, said means including a movable cam member, cams on the member for operating each closure, an arm con- 10 nected to each closure having means engaging its operating cam, each of said cams having a portion for permitting movement of the member during operation of a closure by the other cam, one of said cam portions being adapted to lock one closure during operation of the other, and a double-acting foot pedal lever arrangement for moving said member. 15
6. A waste disposal chute having double closure intakes, including, in combination, an outer pivoted closure and an inner pivoted closure, each of said closures being yielding- ly urged to shut positions, and common means for operating the closures so that one or the other is always shut, said means including a movable cam member, cams on the member for operating each closure, and an arm con- 20 nected to each closure having means engaging its operating cam, each of said cams having a portion for permitting movement of the member during operation of a closure by the other cam, one of said cam portions being adapted to lock one closure during operation of the other. 25
7. A waste disposal chute having double closure intakes, including, in combination, an outer pivoted closure and an inner pivoted closure, each of said closures being yielding- ly urged to shut positions, and common means for operating the closures so that one or the other is always shut, said means including a movable cam member, cams on the member for operating each closure, and an arm con- 30 nected to each closure having means engaging its operating cam, each of said cams having a portion for permitting movement of the member during operation of a closure by the other cam, one of said cam portions being adapted to lock one closure during operation of the other. 35
8. A waste disposal chute having double closure intakes, each including an outer hinged hopper, an inner pivoted closure, said hopper and said closure being normally shut, and means for operating the closures so that one or the other will always be shut, said means including a pedal lever system. 75
9. A waste disposal chute having double closure intakes, each including an outer hinged hopper, an inner pivoted closure, said hopper and said closure being normally shut, and means for operating the closures so that one or the other will always be shut. 80
